Primary Examiner — Calvin E Vansant*(74) Attorney, Agent, or Firm* — Kilpatrick Townsend & Stockton LLP(57) **CLAIM**

The ornamental design for a road milling and planing pick tool, as shown and described.

DESCRIPTION

1. Road milling and planing pick tool

1.1 : Front

1.2 : Back

1.3 : Top

1.4 : Bottom

1.5 : Left

1.6 : Right

This design relates to a pick tool for road planing or milling. The broken lines show portions of a road milling and planing pick tool which form no part of the claimed design.
